THEOPHILUS ELSWORTH SICKELS, OF KENNETT'S SQUARE, PENNSYLVANIA.

Letters Patent No. 99,359, dated February 1, 1870.

IMPROVEMENT IN APPARATUS FOR SINKING PNEUMATIC PILES.

The Schedule referred to in these Letters Patent and making part of the same.

To all whom it may concern:

Be it known that I, THEOPHILUS ELLSWORTH SICKELS, of Kennett's Square, Chester county, and State of Pennsylvania, have invented a new and useful Improvement in the Apparatus for Sinking Pneumatic Piles; and I do hereby declare that the following is a full and exact description thereof, reference being had to the accompanying drawings, and to the letters of reference marked thereon.

When sinking pneumatic piles by the use of air-pressure within the piles, above the atmospheric pressure, it has been the custom to place the air-lock on the top of the pile, and when necessary to lengthen the pile, the condensed air within the pile was first released, then the air-lock was removed, after which other sections of the pile were bolted to the top. To resume the operation of sinking the pile, the air-lock was again placed on top of the pile, and air was again forced into the pile, when the water, sand, or other materials inside the pile were removed by some one of the well-known processes for that purpose.

The difficulties experienced in the operation of adding to the length of the pile, are as follows:

First, when the air-pressure within the pile is released, water, sand, or other material through which the pile is being sunk, is forced up inside the pile by the extreme pressure, which material inside the pile it is expensive to remove.

Second, while the material is thus being forced up inside the pile, the pile is often found to settle out of its true position, which incorrect settlement is caused by the supply of material not having come evenly from around the outside of the pile, owing to obstructions, such as rocks, timbers, or clay, under the edge of the pile, or around the outside thereof.

Third, even in cases when the pile, after the air-pressure has been released, remains in its true position, a very large amount of material will be found to have been forced up into the pile, very much exceeding in quantity that which is required to be excavated to secure an equal amount of settlement while the working air-pressure is maintained.

The object of this invention is to avoid these difficulties, and its nature or character consists in placing an air-tight diaphragm in the pile, to maintain the air-pressure on its lower surface, and thus to maintain the air-pressure on the lower end of the pile, while the air-lock is being removed, other sections of the pile added, and the air-lock replaced, by which maintenance of air-pressure inside the lower end of the pile, the inflowing of water, sand, or other material is effectually prevented, thereby saving expense in sinking pneumatic piles, and diminishing the liability of the pile getting out of true position during the process of lengthening the pile.

In the accompanying drawing—

a a is the pile to be sunk, which is shown broken near the top, to enable the drawing to be made within the size required by the rules of the Patent Office.

b b is the air-lock, through which men and materials may pass to and from the pile without releasing the air-pressure within the pile, the construction and operation of this part being well known.

c c is the diaphragm, figures 1 and 2.

p is the pipe through which air is forced into the pile.

d is a man-hole in the diaphragm c c.

e is a valve, operated by the handle f in the pipe p, through which air is forced into the pile above the diaphragm c c.

h is a check-valve, through which air is forced into the pile below the diaphragm c c, and air may be supplied while the air-lock is removed, in case of any air-leakage from the pile from below the diaphragm c c.

k is a cock, operated by the handle l, to equalize the air-pressure above and below the diaphragm.

When it becomes necessary to lengthen the pile, the workmen who stand at the bottom of the pile ascend through the man-hole d, which they fasten air-tight. Next, the condensed air above the diaphragm c c is released, and when the air-pressure inside the pile is the same as the air-pressure on the outside, the air-lock b b is removed, additional sections of the pile are bolted on, and the air-lock is replaced and bolted to the top of the pile. The workmen then, standing inside, close the upper doors of the air-lock, when air is forced into the pile through the valve e, operated by the handle f. When the air within the pile has attained the desired amount of pressure, the air pressure above and below the diaphragm is equalized by opening the cock k, when the man-hole cover is removed, and the workmen descend to the bottom of the pile, and resume the operation of removing the material within and above the lower edge of the pile.

It is evident that the diaphragm may be located at any desired place in the pile, as may be found most convenient in practice, and it is also evident that the diaphragm may be used when any of the known processes for excavating materials from inside the pile are used.

The diaphragm is made in pieces, so that when the pile is sunk to the proper depth, and sealed at the bottom to exclude water, it may be removed from inside the pile, and be again used in sinking other piles, and any form of diaphragm may be used.

The diaphragm may be used to keep out the uprising materials, if placed low down, notwithstanding the air-pressure is released below it.

Having thus fully described my invention,

What I claim as new, and desire to secure by Letters Patent, is—

The diaphragm, substantially as herein described.

THEOPHILUS ELSWORTH SICKELS.
